UNITED STATES PATENT OFFICE

2,339,179

APPARATUS FOR MAKING CORDED-EDGED
TEXTILES

Rudolf Loeb, Jenkintown, Pa.

Application December 31, 1941, Serial No. 425,227

12 Claims. (Cl. 112—139)

This invention relates to apparatus for making corded-edged textiles, such as curtains, draperies, and the like, of the general character disclosed in my prior United States Letters Patent No. 2,245,285, dated June 10 1941, wherein a hem of predetermined width is formed along one or more of the marginal edges of the article, for example, along the two opposite vertical edges of a hanging drape, although the hem may be also applied to the heading and bottom edges if desired, and wherein a cord is enclosed and anchored in the hem, tightly, at the extreme finished edge of the drape, as and for the purpose set forth in said patent.

The object of the present invention is to provide an efficient apparatus for forming the hem, inserting the cord in the hem, forcing the cord into the extreme outer edge of the hem, and for stitching the drape through the folds of the hem and the underlying fabric of the drape, at the inner edge of the hem, to form the cord-enclosure, and through the primary fold and the underlying fabric, immediately adjacent the enclosed cord, to anchor the cord tightly in the drape, to obviate any relative movement between the cord and the drape fabric, along the edge of the drape, so that the edge of the drape will not wrinkle and will hang straight.

In the accompanying drawings:

Fig. 1 is a general side view of the apparatus;

Fig. 2 is a perpendicular plan view looking in the direction of the arrow, Fig. 1;

Fig. 3 is an enlarged fragmentary plan view immediately above the work table;

Fig. 4 is an enlarged front elevation of the hem-folding mechanism;

Fig. 5 is an enlarged front elevation of the cord-positioning mechanism;

Fig. 6 is an enlarged plan view of the hem and cord-pulling mechanism;

Fig. 7 is a sectional elevation taken on the line 7—7, Fig. 6;

Fig. 8 is a perspective view of the hem-folding and cord-inserting means;

Fig. 9 is a perspective view of the cord-positioning means;

Fig. 10 is a detached perspective view of the cord-positioning foot;

Fig. 11 is a perspective view of the hem and cord-tensioner; and

Fig. 12 is a side elevation of a modified form of hem-puller.

As shown in Figs. 1, 2 and 3, for example, of the aforesaid prior Patent No. 2,245,285, and as shown in Figs. 3, 4, 5 and 9 of the drawings in

the present case, a textile article in the form of curtain or drape is composed of a suitable fabric A and is provided with a hem a of predetermined width. The hem a is composed of a marginal portion of the fabric A folded laterally upon itself, and constitutes a primary fold or main flap a¹ which lies in superposed relation to the main body of the article, parallel to the finished edge thereof. The extreme free edge of the primary fold a¹, constituting a secondary fold or sub-flap a², is reversibly folded and laid in the hem a between the primary fold a¹ and the main body of the fabric A, where it is held in place by one or more rows of stitches b¹, which pass through the superposed hem folds a¹ and a² and the underlying fabric A, inwardly from and parallel to the finished edge of the article.

Within the hem a, immediately adjacent the finished edge of the article, is a cord C, which is confined within a longitudinal cord-enclosing pocket a³. The enclosure a³ is formed in the hem a and extends along the extreme outer edge of the article. The cord-enclosure a³ is completed by a row of stitches b² (Figs. 3 and 9), which pass through the primary fold a¹ and the underlying fabric A, immediately adjacent the inner side of the cord C, to bind the fabric of the cord-enclosure a³ firmly around the cord C, to prevent wrinkling of the fabric along the edge of the article and to anchor the cord in the hem a against relative longitudinal and lateral movement between the two.

In order to form the hem a, a work table 1 is provided with a fabric-folder 2 (see Figs. 4 and 8) which comprises a flattened spirally-bent plate, having one flat portion 3 lying on the work table 1, and a plurality of successively superposed vertically spaced flat portions 4, 5 and 6, joined together successively at their opposite ends by curved portions 7, 8 and 9, and with the terminal end 10 of the inner flat portion 5 bent back upon said portion 5.

The above arrangement forms a bottom channel 11 for the fabric A of the article, a top channel 12 for the primary fold a¹ of a hem a, and an intermediate channel 13 for the secondary fold a².

In one end of the intermediate channel 13, adjacent the turn 9, and spaced from said turn, is a vertical partition 14, which forms a guide opening 15 for the cord C, to place said cord within the hem a immediately adjacent the outer edge of the hem, where the fabric passes around the turn 9 from the channel 11 to the channel 12. As the fabric A advances in the direction of the

arrow z (Fig. 3), the marginal portion along one edge thereof advances into the folder 2 and the folds a^1 and a^2 are thereby automatically folded in. At the same time the cord C is laid in the hem a adjacent the outer edge thereof.

As the folded fabric A, with the cord C therein, leaves the folder 2, the inner edge of the hem a , as formed by the secondary fold a^2 , is pressed down flatly and the fabric is creased at the turn of the fold by a resilient presser finger 16 which is secured to or formed as a part of the folder 2, and which extends rearwardly and downwardly therefrom.

As the folded inner edge of the hem a leaves the presser 16, it passes under a vertically-reciprocating needle bar 20 of a conventional type of sewing machine B, having the usual shuttle or other stitch-locking means and feeding mechanism (not shown), and which, through its needle and cooperating stitch-forming mechanism, forms the row of stitches b^1 in the drape A to complete the hem a , with the cord C lying loosely within the hem pocket, adjacent the marginal edge of the drape.

The hemmed drape fabric A, during the formation of the row of stitches b^1 , is fed rearwardly over the work table 1, by the ordinary feeding mechanism (not shown) of the conventional sewing machine B¹, and is thereafter pulled along the work table 1 by pulling means D, hereinafter described in detail, at the same rate of speed as the fabric is delivered from the sewing machine B¹.

Between the pulling mechanism D and the sewing machine B¹, the fabric A is engaged by a tensioning mechanism E, hereinafter described in detail, to hold the fabric A in a taut condition, to pass through a conventional stitch-forming mechanism of a second conventional sewing machine B² having a vertically-reciprocating needle bar 25 with a needle 24 and other stitch-forming means forming no part of the present invention.

Preferably, the ordinary feeding means of the conventional sewing machine B² is rendered inoperative or removed, in view of the fabric being advanced past the needle bar 25, etc., by the pulling mechanism D under tension provided by the tensioning means E.

Immediately after leaving the tensioning means E, the portion of the hem a of the fabric A lying adjacent the outer edge of the article is engaged by cord-positioning mechanism F, which, as shown in Figs. 3, 5 and 9, includes an anvil or positioning block 30 secured to the work table 1, as by screws 31, 31. The positioning block 30 is provided with a vertical wall 32, for engagement with the extreme outer edge of the hem a .

The hem-engaging surface 32 of the cord-positioning anvil 30, as shown in Fig. 3, is offset laterally with respect to the hem-folder 2, on the work table 1, to place the fabric of the hem a under a lateral tension, in addition to the longitudinal tension effected by the pulling mechanism D.

Cooperating with the work-engaging block 30 is a shoe 33, which, as shown in Figs. 5 and 10, is provided with a flat under surface 34 adapted to press the hem fabric downwardly against the work table 1, and to slide or sled over the hem fabric as the hem fabric is pulled under the shoe 33. The forward end 35 of the flat sledging surface 34 is curved upwardly to act as a flat iron, to smoothen the fabric as it advances under the sledging or ironing surface 34.

Along the edge of the shoe 33 which normally

lies adjacent the vertical wall 32 of the work-engaging block 30, the shoe 33 is rabbeted, as shown at 36, Figs. 5 and 10, to provide a right angle recess, including a flat horizontal under surface 37 parallel to the under surface 34, and a vertical surface 38 parallel to the vertical wall 32 of the anvil 30. Toward the forward end 35 of the surface 34, the vertical surface 38 of the shoe 33 curves outwardly, as shown at 39, Fig. 3, and lies in divergent relation to the wall 32 of the anvil 30.

Upon referring to Fig. 9, it will be apparent that, as the fabric A advances in the direction of the arrow y , the shoe 33 presses the primary fold a^1 down firmly against the underlying portion of the fabric A; and that the convergency of the curved surface 38 of the shoe 33 with respect to the vertical surface 32 of the anvil 30 forces the cord C laterally within the hem a , into the extreme outer edge of the hem pocket, as shown in Fig. 5. Due to the longitudinal and transverse tensioning of the fabric A, as afforded by the pulling means D, the fabric of the hem a is pulled tightly around the cord C, to produce the corded edge of the article, in the form of a cord-enclosing pocket a^3 . The edge pocket a^3 is then completed and made permanent by a row of stitches b^2 , which pass through the primary fold a^1 and the underlying fabric A immediately adjacent the inner side of the cord C, said row of stitches being produced by the needle 24, etc. of the sawing machine B².

The cord-positioning shoe 33 is carried by one end of a lever 40 which is pivoted, intermediate its ends, at 41, to a bracket 42 secured to the work table 1. A flat spring 43, operating beneath the opposite end of the lever 40, tends at all times to rock the lever about its pivot and thereby press the shoe 33 downwardly against the fabric forming the hem a . An adjustable stop 44, which is carried by the bracket 42, prevents the shoe from being forced so strongly against the hem fabric as to interfere with the movement of the fabric along the work table 1. A release cam 45, pivoted at 46 to the bracket 42, is provided to raise the shoe 33 to an inoperative position while threading a strip of fabric A through the apparatus originally.

The cord C is drawn from any remotely situated and suitable cone, spool, or other supply, through a plurality of guide eyes 47 and 48 which apply tension to the cord as it enters the hem a and as the hem is being folded in the folder 2. The eyes 48, in the present instance, are formed in a bracket 49, which is secured to the outer convolution of the spirally-bent plate which constitutes the folder 2. The eye 48 is formed in an extension 50 of the partition 14, which produces the guide channel 15 for the cord in the one end of the inner fabric channel 13 of the folder 2.

The pulling mechanism D comprises a pair of rolls 51 and 52 which are carried by shafts 53 and 54, respectively. The shafts 53 and 54 are rotatably mounted, adjacent the opposite ends of said rolls, in brackets 55, which are rigidly secured to the work table 1, only one of said brackets being shown in the present instance.

The rolls 51 and 52 are slightly reduced in diameter adjacent the bracket 55, as shown at 56 and 57, respectively, the reduction in the diameter of the rolls being provided to compensate for the difference in the thickness between the multi-ply hem a and the single-ply of the fabric 75 A so that rotation of the rolls 51 and 52 normally

would feed the fabric A uniformly from side to side thereof.

In order to pull the fabric, a nip roll 60 is adapted to cooperate with the reduced portions 55 and 57 of the rolls 51 and 52 to pinch the fabric therebetween. In order to compensate for the difference in thickness between the hem a and the edge pocket a³, in which the cord C is confined, the roll 60 is provided with a portion 61 of one diameter, to pinch the hem a between said portion and the reduced portion 57 of the roll 52, and a portion 62 of smaller diameter than the portion 61, which is adapted to pinch the cord-containing pocket a³ between its periphery and the periphery of the portion 56 of the roll 51.

The pinch roll 60 is secured to a shaft 63, which is rotatably mounted in bearings 64, 64 carried by a swing frame 65. The swing frame 65 is provided with bearings 66, which are pivotally mounted on a shaft 67. The shaft 67 is provided with an eccentric portion 68 which is mounted in a bearing 69 forming part of the bracket 55, and is clamped in a predetermined position by a nut 70 threaded onto the outer end 71 of the eccentric shaft section 68, to clamp the shaft 67 in any given position. Upon loosening the clamp 70, and rotating the shaft portion 68 in the bearing 69, the eccentric portion 67 of the shaft may be moved laterally, carrying with it the swing frame 65 and the pinch roll 60, whereby the roll 60 may be adjusted to cause the portions 61 and 62 thereof to bear with equal force against the hem a and the cord pocket a³, and pinch the same with equal force against the portions 56 and 57 of the rolls 51 and 52, respectively, whereby uniform tension will be placed upon the hem a and the cord pocket a³.

In the present instance, the tensioning means E comprises a triangular block 75, and a pair of fingers 76, 76, extending parallel to and adjacent the lower sharp corners 77 of the triangular block 75, with slots 78 formed between said edges of the block and the fingers 76. The block 75, etc., is mounted on the work table 1 transversely to the travel of the fabric A from the sewing machine B¹ to the sewing machine B².

The fabric A is threaded under one finger 76, through the slot 78 adjacent thereto, up one side of the block 75, over the relatively sharp top edge 79 of the triangular block 75, then downwardly over the second side of said block, through the second slot 78, and under the second finger 76. This arrangement provides a snubbing action on the hem a between the two sewing machines B¹ and B², it being remembered that, as previously noted, the fabric is fed away from the sewing machine B¹ by the conventional feeding mechanism thereof, and is normally in a relatively loose state as it leaves the first said sewing machine B¹.

In order to position the cord C in the extreme edge of the hem a by the shoe 33, and in order to stitch through the hem a immediately adjacent the cord pocket a³, it is necessary to maintain the hem a under tension prior to its passage to the cord-positioning means F and the needle bar 25 of the second sewing machine B².

Pivoted at 81 to the side of the snubbing block 75 nearest the second sewing machine B² is a spring metal finger 80 having a foot portion 82 which bears on the upper side of the hem a at and adjacent the inner extreme edge thereof, to prevent puckering of the fabric as the hem a comes under the influence of the cord-positioning shoe 33. The spring finger 80 is provided

with an offset portion 83 which resiliently bears against a flat horizontal projecting surface 84 formed on the side of the triangular block 75, which tends to keep the foot 82 down firmly in 5 resilient contact with the hem fabric a. A lever 85, formed integral with the finger 80, is adapted to raise the foot 82 when threading the fabric through the tensioning means E.

Power from any suitable source may be applied 10 to the apparatus through a pulley 86 secured to the main drive shaft 87 of the first sewing machine B¹. The main shaft 87 of the sewing machine B¹ is provided with an extension 88 which is rotatably mounted in bearings 89, 89 15 secured to the work table 1. A yoke frame 90 is provided with axially-aligned bearings 91, 91, through which the shaft 88 passes, and a right angle bearing 92 for one end of a power take-off shaft 93. The opposite end of the shaft 93 is 20 rotatably mounted in a bearing 94 carried by a second yoke frame 95, which is also provided with axially-aligned bearings 96, 96 through which an extension 97 of the main shaft 98, of the second sewing machine B², passes. Bearings 99, 99, secured to the work table 1, support the shaft extension 97 for rotation. The shaft 93 is driven 25 through a pair of mitre gears 100, one of which is splined to the shaft 88, while the second is secured to one end of the shaft 93, within the yoke frame 90. A second pair of mitre gears 101, having one gear secured to the second end of the shaft 93 and the other splined to the shaft 97, provide the power for the second sewing machine B².

35 As shown in Fig. 2, the main power shaft 88 is provided with a pinion 102 which meshes with a gear 103. Fast to the gear 103 is a pinion 104, which meshes with a gear 105 (see Fig. 1). Fast to the gear 105 is a sprocket wheel 106, in the 40 present instance, about which passes a sprocket chain 107. The sprocket chain 107 also passes around a sprocket wheel 108, which is secured to the shaft 53 of the pulling roll 51. As shown in Fig. 7, the shaft 53 is also provided with a gear 45 109 which meshes loosely with a gear 110 secured to the shaft 63 of the pinch roll 60.

Either one or both of the sewing machines B¹ and B² may be mounted on the table 1 in such a manner as to be shifted axially of their main 50 shafts 88 and 97, respectively, for changing the lateral relationship between the needle bars 20 and 25, respectively, of said machines for operating on curtains, etc., having hems a of different widths, for properly positioning the row of 55 stitches b¹ adjacent the inner edge of the hem a, and the row of stitches b² adjacent the outer edge of the hem. For this purpose, the mitre gears on said main shafts 88 and 97, as noted above, are splined to their respective shafts and 60 the shafts themselves are capable of being shifted axially within said mitre gears and the supporting bearings 89, 89 and 99, 99, respectively. The pinion 102, under such circumstances, would also be splined to the shaft 88.

65 In order to adjust the folder 2 on the table 1, to effect formation of hems of different widths, the folders of different sizes, respectively, are each provided with a tongue 111, slotted at 112 for the passage of a clamping bolt 113, by which 70 the folder 2 may be secured in the position to which it is adjusted.

In the tensioning apparatus E, the snubbing block 75 and the fingers 76, 76 are secured to a plate portion 114, having elongated slots 115 for the reception of securing screws 116, by which

said tensioning mechanism may be adjusted and secured in position on the work table.

Through the driving mechanism previously described, the sewing machines B¹ and B² and the pulling mechanism D are operated continuously in synchronized relation to each other. However, if desired, the rolls of the pulling mechanism may be intermittently operated in synchronization with the stitch-forming and fabric-feeding mechanisms of the sewing machines, by the mechanism shown in Fig. 12. The main shaft 117 of a sewing machine B³, for example, is provided with an eccentric 118, which is surrounded by a strap 119 having a reach rod 120 connected at 121 to a lever 122. The lever 122 is rotatably mounted on a shaft 123 which would be adapted to support and drive an upper pulling roll 124 through an intermittent clutching arrangement. The clutch mechanism comprises a disc 125 secured to the shaft 123 and having recesses 126 in which clutch rolls or balls 127 are freely mounted with springs 128 arranged to force said balls into one end of each recess, between the converging base surface 129 of the recess and the inner peripheral surface 130 of a hollow hub 131, attached to and from which the lever 122 extends.

As the lever 122 is rocked in one direction, the clutch elements 127 take hold and lock the disc 125 to the hub 131, causing a rotation of the roll 124. As the lever 122 rocks in the opposite direction, the balls or rolls 127 are released and disconnect the roll 124 from the hub 131, thus leaving the roll 124 standing idle.

The fabric is gripped between the periphery of the roll 124 and a second pinch roll 132 having a shaft 133 on which is secured a gear 134. The gear 134 meshes with a similar gear 135 secured to the shaft 123 to which is also secured the roll 124.

In this instance, the sewing machine B³ would be provided with the conventional feeding mechanism, timed with the stitch-forming mechanism to advance the fabric intermittently under the needle bar, and the pulling rolls 124 and 132 would be correspondingly operated intermittently.

The above noted mechanism has particular value in cases where one may choose to form the hem a, with the cord C loose therein, on one machine and to force the cord into the edge of the hem and stitch the same in place on another machine, remote to the hem-forming machine. While such arrangement is possible, it is not preferable, for obvious reasons, and is only mentioned herein as a possible alternative for the preferred form of apparatus previously described, wherein the hem and the cord pocket are formed from beginning to end in one and the same apparatus, which obviates extra handling, etc., and assures the cord being properly positioned within the hem a immediately following the formation of such hem.

I claim:

1. Apparatus for making corded-edged textiles, comprising means for folding a fabric laterally upon itself adjacent one of its edges, means for inserting a cord in the lateral fold, means for stitching the inner edge of the lateral fold to the underlying fabric to enclose the cord, means for forcing the cord laterally into the outer edge of the lateral fold, means for stitching the lateral fold to the underlying fabric adjacent the inner side of the cord, means following said second stitching means for pulling the fabric through said second stitching means, and means interme-

diate said first and second stitching means for applying tensioning resistance to the movement of the fabric by said pulling means.

2. Apparatus for making corded-edged textiles, comprising means for folding a fabric laterally upon itself adjacent one of its edges, means for laying a cord in the fold, means for stitching the free edge of the fold to the underlying fabric, means for pulling the fabric longitudinally, means intermediate said stitching means and said pulling means for applying tensioning resistance to the pull of the fabric by said pulling means, means intermediate said tensioning means and said pulling means for forcing the cord into the outer edge of the stitched fold, and means intermediate said cord-forcing means and said pulling means for stitching the fabric through said fold adjacent the inner side of said cord.

3. Apparatus for making corded-edged textiles, comprising means for folding a fabric laterally upon itself adjacent one of its edges, means for laying a cord in the fold, means for stitching the free edge of the fold to the underlying fabric, means for pulling the fabric longitudinally, means intermediate said stitching means and said pulling means for applying tensioning resistance to the pull of the fabric by said pulling means, means intermediate said tensioning means and said pulling means for forcing the cord into the outer edge of the stitched fold, and means intermediate said cord-forcing means and said pulling means for stitching the fabric through said fold adjacent the inner side of said cord, said cord-forcing means and said second stitching means being arranged in laterally-offset relationship to said folding and first stitching means.

4. In an apparatus for making corded-edged textiles, means for folding a fabric laterally around a cord, means for tensioning the fabric and the cord including means for pulling the fabric and cord longitudinally of the latter, a shoe for engaging and tightening the fabric around the cord, a fixed anvil having a surface for engaging the folded edge of the fabric at one side of the cord, a surface on the shoe parallel to said anvil surface for engaging the fabric at the opposite side of the cord for holding the folded fabric and the cord in tightened relation, and means for stitching the tightened fabric adjacent the cord.

5. In an apparatus for making corded-edged textiles, means for folding a fabric laterally around a cord, means for tensioning the fabric and the cord including means for pulling the fabric and cord longitudinally of the latter, a shoe for engaging and tightening the fabric around the cord, a fixed anvil having a surface for engaging the folded edge of the fabric at one side of the cord, a surface on the shoe parallel to said anvil surface for engaging the fabric at the opposite side of the cord, and a third surface between and at right angles to said parallel surfaces for holding the folded fabric and the cord in tightened relation, and means for stitching the tightened fabric adjacent the cord.

6. In an apparatus for making corded-edged textiles, means for folding a fabric laterally around a cord, means for tensioning the fabric and the cord including means for pulling the fabric and cord longitudinally of the latter, a shoe for engaging and tightening the fabric around the cord, a fixed anvil having a surface for engaging the folded edge of the fabric at one side of the cord, a surface on the shoe parallel

to said anvil surface for engaging the fabric at the opposite side of the cord, and a third surface between and at right angles to said parallel surfaces for holding the folded fabric and the cord in tightened relation, said parallel surfaces being in convergent relationship to each other at one end of the shoe to guide the fabric and cord into said tightening relationship, and means for stitching the tightened fabric adjacent the cord.

7. In an apparatus for making corded-edged textiles, means for folding a fabric laterally around a cord, means for stitching the folded fabric adjacent the cord, and means for pulling the folded fabric and the cord uniformly comprising a pair of parallel laterally-spaced rolls, a pinch roll intermediate and adapted to cooperate with said parallel rolls, said pinch roll having a portion of one diameter adapted to pinch the folded fabric adjacent the enclosed cord against one of said pair of rolls, and a portion of lesser diameter adapted to pinch the fabric enclosing the cord against the other of said pair of rolls.

8. In an apparatus for making corded-edged textiles, means for folding a fabric laterally around a cord, means for stitching the folded fabric adjacent the cord, and means for pulling the folded fabric and the cord uniformly comprising a pair of parallel laterally-spaced rolls, a pinch roll intermediate and adapted to cooperate with said parallel rolls, said pinch roll having a portion of one diameter adapted to pinch the folded fabric adjacent the enclosed cord against one of said pair of rolls, a portion of lesser diameter adapted to pinch the fabric enclosing the cord against the other of said pair of rolls, and means for varying the relationship of the axis of said pinch roll relative to the axes of said pair of rolls to effect uniform pinching of the fabric at said pair of rolls respectively.

9. In an apparatus for making corded-edged textiles, means for folding a fabric laterally around a cord, means for stitching the folded fabric adjacent the cord, and means for pulling the folded fabric and the cord uniformly comprising a pair of parallel laterally-spaced rolls, a pinch roll intermediate and adapted to cooperate with said parallel rolls, said pinch roll having a portion of one diameter adapted to pinch the folded fabric adjacent the enclosed cord against one of said pair of rolls, a portion of lesser diameter adapted to pinch the fabric enclosing the cord against the other of said pair of rolls, a frame supporting the pinch roll for free movement perpendicular to a plane common to the axes of said pair of rolls, and means for varying the position of the axis of said pinch roll laterally in a plane substantially parallel to said common plane to regulate the pinch of said pinch roll on the fabric with respect to said pair of rolls, respectively.

10. In an apparatus for making corded-edged textiles, means for folding a fabric laterally around a cord, means for stitching the folded

fabric adjacent the cord, and means for pulling the folded fabric and the cord uniformly comprising a pair of parallel laterally-spaced rolls, a pinch roll intermediate and adapted to cooperate with said parallel rolls, said pinch roll having a portion of one diameter adapted to pinch the folded fabric adjacent the enclosed cord against one of said pair of rolls, a portion of lesser diameter adapted to pinch the fabric enclosing the cord against the other of said pair of rolls, a frame supporting the pinch roll for free movement perpendicular to a plane common to the axes of said pair of rolls, and an eccentric pivotal mounting for said frame to vary the position of the pinch roll parallel to said common plane in directions laterally with respect to the axes of said pair of rolls.

11. Apparatus for making corded-edged textile articles, comprising means for folding a marginal portion of a fabric laterally upon the body portion thereof along one edge of the fabric, means for inserting a cord in the fold during said folding, hemming means including coordinated stitching and feeding mechanisms for initially stitching the free edge of said marginal portion to the underlying body portion in laterally spaced relation to the line of said fold to form a hem loosely enclosing the cord, means remote to said hemming means in a direction longitudinally of said hem for tightening the fabric around the cord, coordinated stitching and feeding means adjacent said tightening means for stitching the fold to the underlying body of the fabric adjacent the cord and for advancing the fabric to effect anchoring of the cord in the hem, and means intermediate said hemming means and said tightening means for tensioning the fabric and cord for entry to said tightening means.

12. Apparatus for making corded-edged textile articles, comprising means for folding a marginal portion of a fabric laterally upon the body portion thereof along one edge of the fabric, means for inserting a cord in the fold during said folding, hemming means including coordinated stitching and feeding mechanisms for initially stitching the free edge of said marginal portion to the underlying body portion in laterally spaced relation to the line of said fold to form a hem loosely enclosing the cord, means remote to said hemming means in a direction longitudinally of said hem for tightening the fabric around the cord, coordinated stitching and feeding means adjacent said tightening means for stitching the fold to the underlying body of the fabric adjacent the cord and for advancing the fabric to effect anchoring of the cord in the hem, means intermediate said hemming means and said tightening means for tensioning the fabric and cord for entry to said tightening means, and means synchronized with and supplementing the last said feeding and stitching means for drawing the fabric through said tightening and tensioning means.

RUDOLF LOEB.
